MOUNTING FOR LOCK MECHANISM

Edward N. Jacobi, Milwaukee, Wis., assignor to
 Briggs & Stratton Corporation, Milwaukee,
 Wis., a corporation of Delaware

Application July 26, 1948, Serial No. 40,650

12 Claims. (Cl. 70—370)

1 This invention relates to locks and refers more particularly to lock switches of the type adapted to be mounted on the back of an instrument panel of an automobile with the lock plug exposed for key actuation at the front of the panel.

In installations of this nature heretofore available, the lock body ordinarily had a bore of a diameter to snugly receive the lock mechanism and it was customary to secure the lock mechanism in the bore of the body by means of a retaining pin carried by the lock mechanism casing.

In many instances the lock mechanism (i. e., the plug, its casing and the tumblers) was positioned in the bore with the forward end of the lock plug spaced inwardly of the end of the lock body to accommodate a bezel and its mounting cylinder. With such a construction it is necessary to cast the bezel receiving end of the body with a counterbore to provide the proper clearance for the key and the bezel which extends into the bore to cooperate with the lock plug.

The opposite end of the lock switch body has a second counterbore to rotatably receive the switch mechanism. Hence, with a cast body having a counterbore at each end it is necessary to use two cores abutting one another and withdrawn from opposite ends. This complicates the casting molds and casting operation.

It is therefore an object of this invention to provide improved means for mounting a lock mechanism in the bore of a cast lock body which permits the bore of the body to be greater in diameter than the casing of the lock mechanism thereby eliminating the counterbore at the bezel receiving end of the body.

More specifically it is an object of this invention to provide mounting means for the lock mechanism of an ignition switch lock which enables casting of the switch body using but a single core.

A further object of this invention is to so construct the means for securing the lock mechanism in the bore of the body that it inherently prevents the lock casing from rattling and in addition keeps the key from rattling when the lock plug is in its unlocked position.

Still another object of this invention is to provide improved means integral with the lock mechanism mounting means for retaining a bezel over the end of the lock body.

With the above and other objects in view, which will appear as the description proceeds, this invention resides in the novel construction, combination and arrangement of parts substantially

2 as hereinafter described and more particularly defined by the appended claims, it being understood that such changes in the precise embodiment of the herein disclosed invention may be made as come within the scope of the claims.

The accompanying drawings illustrate two complete examples of the physical embodiment of the invention constructed according to the best modes so far devised for the practical application of the principles thereof, and in which:

Figure 1 is a side elevational view of a lock switch having its lock mechanism mounted therein in accordance with this invention, parts being broken away and shown in section, on the plane of the line 1—1 in Figure 2;

Figure 2 is a cross-sectional view of the lock switch taken along the plane of the line 2—2 in Figure 1;

Figure 3 is a view in cross-section similar to Figure 2 and showing the lock plug turned toward unlocked position by its key;

Figure 4 is an enlarged fragmentary view illustrating the manner in which the spring blade retaining means, shown in perspective in Figure 5, is assembled with the lock body;

Figure 5 is a separated detail perspective view showing the front portion of the lock switch body, the spring blade, and the rear portion of the lock mechanism;

Figure 6 is a bottom view of the assembled lock, portions being broken away and shown in section on the plane of the line 6—6 in Figure 2;

Figure 7 is a front elevational view of the lock switch, with a portion of the bezel cut away to show a modified construction wherein the spring blade mounting means also serves to hold the bezel in place;

Figure 8 is a view similar to Figure 6 with its portion in section taken along the plane of the line 8—8 in Figure 7; and

Figure 9 is a detail perspective view of the modified spring retaining blade.

Referring more particularly to the accompanying drawings in which like numerals indicate like parts, the numeral 5 designates generally a lock switch of the type adapted to be mounted upon the instrument panel 6 of an automobile at the rear thereof.

The lock switch comprises a body having an enlarged cup-shaped housing 7 at the rear to receive switch mechanism (not shown). The switch mechanism forms no part of this invention, but if needed a detailed description thereof may be found in my copending application, Serial

No. 19,529, filed April 7, 1948, and entitled "Electric Switch."

Extending forwardly from the cup-like housing 7 is an elongated barrel 8. The front end of this barrel 8 has a number of forwardly projecting arms 9 by which the entire structure is attached to the instrument panel. The manner in which the attaching arms are secured to the panel constitutes the subject matter of another of my co-pending applications, Serial No. 39,008, filed July 16, 1948, now Patent No. 2,558,852, dated July 3, 1951, and entitled "Ignition Lock Switch."

The lock mechanism 10 is adapted to be received in the bore 11 of the barrel 8 and comprises a pin tumbler lock plug 12 rotatable in a casing 13. The cross-sectional dimension of the casing 13 is considerably smaller than that of the bore 11. The casing is positioned in the upper portion of the bore and held there by means of a spring blade 14.

The spring blade 14 is a substantially flat rectangular piece of spring steel, centrally cut out as at 15 to define two parallel opposite longitudinal sides 16. These sides 16 are received in longitudinal grooves 17 formed in the wall of the bore 11, and the spaced transverse end portions 18 of the blade bear against the underside of the lock casing 13 near the ends thereof.

Ears 19 extending laterally from the forward end of the spring blade engage between a pair of pins 20 on two of the arms 9 and the adjacent end wall 9' of the barrel to prevent axial displacement of the spring blade.

In assembly the spring blade 14 is slid into the bore with its sides 16 riding in the longitudinal grooves 11 until the ears 19 engage the pins 20, and since the ears 19 are slightly inclined with respect to the plane of the spring blade 14 they cam themselves over the pins to snap in place between the pins and the end wall 9'. This is shown in Figure 4.

Insertion of the lock mechanism is effected by sliding the lock casing 13 with the plug 12 therein into the bore 11 from its front end and between the spring blade 14 and the top of the bore 11 with a longitudinal rib 21 extending along the top of the casing 13 received in a slot 22 formed in the top of the bore 11. The upward force of the spring blade 14 against the casing 13 prevents disengagement of the rib 21 from the slot 22 to thereby preclude rotation of the lock casing 13 relative to the lock body 6 and also holds the casing 13 against rattling.

To properly position the lock mechanism axially within the bore 11 and to preclude inward longitudinal shifting of the lock mechanism, the lock casing 13 is provided with a shoulder 23 on the underside at the rear thereof. The shoulder 23 abuts the edge of a medial hump 24 on the end portion 18 at the rear of the spring blade 14. A pin 25 yieldingly projected from the top of the casing 13 adjacent to its rear end cooperates with an edge 26 at the junction of the barrel 8 and housing 7 to prevent axial shifting of the lock mechanism in the opposite direction, the pin 25 being held against depression as long as the plug is in its locked position of rotation.

The shoulder 23 which abuts the front edge of the hump 24 to restrain the lock mechanism against inward longitudinal shifting is formed by cutting away part of the bottom wall of the casing. This exposes the adjacent rear end portion of the lock plug for direct engagement by the hump 24 which thus presses against the plug and keeps the same from rattling.

Removal of the lock mechanism is effected by turning the lock plug to the unlocked position, depressing the pin 25, and withdrawing the casing 13. Access to the pin 25 is gained through an aperture 27 in the lock body.

A cap 28 is disposed over the end of the lock plug 12 which extends forwardly of the end of the lock casing 13, to cooperate with a funnel-shaped bezel 29, fitted over the ends of the attaching arms 9 to provide a neat appearance for the front end of the lock, and a pilot bearing for the front end of the lock plug. The bezel also serves to guide the key into the keyway of the lock plug.

The keyway of the lock plug is open at its bottom to be closed by the bore in the casing 13. Hence as the pin tumblers bear against the serrated edge of the key in the locked position they press the plain straight back edge of the key against the bore of the casing. This assists in eliminating rattling of the key and the plug in the locked position.

However, in the unlocked position the pin tumblers do not bear against the edge of the key and hence the key has a tendency to rattle. To eliminate this annoyance the spring blade 14 has a finger 30 extending from the front end of one of its side members 16. As may be seen in Figure 3, the end of the finger 30 bears against the plain edge of the key to urge the key against the top of the key slot and thereby prevent rattling of the key in the unlocked position. The portion of the cap 28 covering the open end of the key slot is cut away as at 28' (see Figure 6) to allow the finger to reach through the cap and bear against the key.

The diametrically opposite portion of the cap is also cut away and the key slot breaks through the top of the plug at this point to enable the key slot to be illuminated by a light in back of the instrument panel above the barrel 8. A hole 31 in the top of the barrel allows the light to enter the bore therein and to reflect off the walls of the bore until it enters the keyway of the lock plug through the two cut out portions in the cap 28 on the end of the lock plug.

The fastening for the bezel 29 is the same as that described at length in the aforesaid co-pending application, Serial No. 39,008 and includes a spring ring 32 confined between cam surfaces 33 on the front ends of the attaching arms 9 and the inturned edge 34 of the bezel.

In Figures 7, 8 and 9 the bezel is shown held in place in a manner obviating the spring ring 32. In its stead spring fingers 35 are extended from the front end of the spring blade 14 to project through the hole in the instrument panel and engage behind the inturned edge of the bezel. The fingers 35 are substantially L-shaped and their extremities, which point outwardly, are pointed to provide ascending and descending cam surfaces over which the edge 34 of the bezel rides as it is applied; and when the bezel is in place the resiliency of the spring fingers 35 projects their pointed ends into the circumferential channel in the bezel behind its edge 34 to hold the bezel in place.

The spring blade of this modified embodiment of the invention also provides a slightly different way of holding the key against rattling in the unlocked position. It consists of an upwardly directed tongue 36 having a flat end 37 positioned to bear against the underside of the projecting front end portion of the lock plug at a

point to press against the key in the unlocked position of the plug.

From the foregoing description taken in connection with the accompanying drawings, it will be apparent that this invention provides an inexpensive and practical manner of mounting a lock plug and its casing in the barrel or body of a lock switch, which has the advantage of simplifying the die casting of the lock switch by obviating the need for more than one axially pulled core, and of holding the lock casing, the plug therein and the key against rattling whether the plug is in its locked or unlocked position.

What I claim as my invention is:

1. In a lock of the character described: a lock body having a bore; lock mechanism inside said body bore, including a bored lock casing and a lock plug rotatable therein, said casing being smaller in diameter than the bore of the body and having a portion of its side wall so formed as to expose part of the side wall of the plug; and means for holding the lock mechanism in the bore of the body including a spring blade carried by the body and extending across a portion of the body bore adjacent said portion of the side wall of the casing, said spring blade having means pressing against said exposed part of the plug to keep the same from rattling in the casing and means biasing the casing into firm engagement with the wall of the bore.

2. The lock set forth in claim 1 further characterized by the fact that the lock plug protrudes from the mouth of its casing and is formed to expose an edge of a key inserted into the lock plug; and by the provision of a resilient finger on the spring blade positioned to press against said edge of the key when the lock plug is turned to its unlocked position to thus hold the key and plug against rattling.

3. In a lock of the character described: a body having a bore; a lock mechanism including a lock casing and a plug rotatable therein, said lock casing being smaller in its cross-sectional dimensions than the bore and being shorter than the bore so that when the lock mechanism is in position in the bore sufficient space is left at the front end thereof to accommodate the central portion of a bezel; supporting ledges on the opposite side walls of the bore; a spring blade removably engaged with said ledges and pressing against the side of the lock mechanism to hold the same in place in the bore, with a portion on the lock plug protruding from the front end of the casing; and a bezel secured in place at the front end of the body with its central portion receiving said portion on the front end of the plug to provide a pilot bearing therefor.

4. In a lock of the character described: a body having a bore; lock mechanism within the bore and comprising a casing and a lock plug rotatable therein, said casing being smaller in diameter than the bore; supporting ledges in opposite side walls of the bore; a spring blade resting upon said ledges and having its medial portion bearing against the side of the casing to hold the lock mechanism against one side of the bore, part of the casing wall being cut away to expose the lock plug; a part on said spring blade engaging and pressing against the exposed part of the plug; and interengaging abutments on the body and spring blade holding the blade against shifting endwise of the bore.

5. The lock set forth in claim 4 further characterized by the provision of: a shoulder on the casing formed by the cutout which exposes the

plug; and an edge on the spring blade engageable with said shoulder to restrain endwise movement of the lock plug in one direction.

5. In a lock of the character described: a body having a bore with a longitudinal channel in the wall thereof; lock mechanism within the bore and including a casing and a lock plug rotatable therein, the casing being smaller in diameter than the bore; a longitudinal rib on the casing fitting into the channel to restrain the casing against turning; supporting ledges on the walls of the bore so positioned that a plane joining said ledges is substantially parallel to the bottom of said channel; and a spring blade extending across the bore and supported on said ledges with the medial portion of the blade bearing against the side of the lock casing opposite its longitudinal rib, said blade being biased to press the casing toward the channel and thereby hold the longitudinal rib in the channel.

10. The lock structure set forth in claim 6 further characterized by the provision of: spring detent means for holding the spring blade in position, said detent means comprising an abutment on the body, and a spring-arm on the blade adapted to snap over the abutment during assembly of the blade with the body.

15. In a lock of the character described: a body having a bore; lock mechanism in the bore comprising a lock casing and a lock plug rotatable therein and having a portion projecting forwardly therefrom, the casing being smaller in diameter than the bore; a bezel having a hole of a size to rotatably receive the projecting portion 20 on the plug; cooperating means on the bezel and the body holding the bezel centered with respect to the body; spring means carried by the body and bearing against one side of the lock mechanism to hold the opposite side thereof engaged 25 with one side of the bore in the body; and a connection between said spring means and the bezel for retaining the bezel in place and against said centering means on the body.

30. The lock set forth in claim 8 further characterized by the fact that: said spring means comprises a spring blade extending across the bore in the body near one side thereof and pressing against the adjacent side of the lock casing, and spring fingers protruding from the blade and engaging behind an inturned marginal edge on 35 the bezel.

35. The lock set forth in claim 8 further characterized by the fact that: said spring means comprises a spring blade extending across the bore in the body near one side thereof and pressing against the adjacent side of the lock casing, and spring fingers protruding from the blade and engaging behind an inturned marginal edge on 40 the bezel.

40. In a lock of the character described: a lock body having a bore; lock mechanism inside said bore including a lock casing and a lock plug rotatable therein, said casing being smaller in diameter than the bore; means for holding the lock body inside the bore and against one side thereof comprising a spring blade carried by the body and extending across a portion of the bore in engagement with the side of the lock casing remote from said side of the bore to bias the casing against said side of the bore; and cooperating means on the body and the casing held interengaged by said spring blade for precluding turning of the casing in the bore.

45. In a lock of the character described: a lock body having a bore; a key controlled lock mechanism inside said bore including a lock casing and a lock plug rotatable therein, said casing having a shoulder thereon transverse to its axis; means for holding the lock body inside the bore and against one side thereof comprising a spring blade carried by the body and having a part engaging the lock casing on the side thereof remote from 50 said side of the bore to bias the lock casing against

said side of the bore; and an abutment on the spring engaging said shoulder on the lock casing to preclude axial displacement of the casing in at least one direction with respect to the spring; cooperating means on the body and the casing at their areas of engagement for precluding turning of the casing in the bore; and cooperating elements on the lock body and the spring for precluding axial displacement of the spring with respect to the body.

12. In a lock of the character described: a body having a bore opening to its front; a lock mechanism inside said bore including a casing and a key controlled plug rotatable therein and having its front end accessible at the front of the body; a bezel on the front of the body having an aperture through which the front of said plug is accessible, and having an inturned flange at its rear; a spring blade carried by the body and having a part engaging a part of the lock mechanism to bias the same into firm engagement with the wall of the

bore in the body; and a pair of forwardly extending spring fingers on the spring blade hooked into said flange on the bezel to retain the bezel on the front of the body and to hold its aperture axially aligned with said plug.
